(57) CLAIM

The ornamental design for a dispenser, as shown and described.

DESCRIPTION

FIG. 1 is a perspective view showing the new design for a dispenser;

FIG. 2 is a right side view thereof, a left side view being a mirror image thereof;

FIG. 3 is a front view thereof;

FIG. 4 is a rear view thereof;

FIG. 5 is a top view thereof;

FIG. 6 is a bottom view thereof; and,

FIG. 7 is a perspective view thereof showing the dispenser with flags and a note.

The broken lines in FIGS. 1-7 are included for the purpose of showing portions of the dispenser that form no part of the claimed design.

1 Claim, 4 Drawing Sheets
